UNITED STATES PATENT OFFICE.

HENRY B. BELDEN, OF TOLEDO, IOWA.

DESIGN FOR A CASE FOR WRITING UTENSILS.

SPECIFICATION forming part of Design No. 32,634, dated May 8, 1900.

Application filed April 2, 1900. Serial No. 11,268. Term of patent 14 years.

To all whom it may concern:

Be it known that I, HENRY B. BELDEN, a citizen of the United States, residing at Toledo, in the county of Tama and State of Iowa, have invented and produced a new and original Design for a Case for Writing Utensils, of which the following is a specification, reference being had to the accompanying drawings, forming part hereof.

Figure 1 shows in perspective my complete design. Fig. 2 shows a vertical central transverse sectional view of the same.

The leading or material feature of my design consists of a flat base 10. At the ends of the base are two flat uprights 11. At the top of the uprights is a cross-piece 12 to extend from one upright to the other and having the rounded central portion 13. A short distance below the cross-piece 12 is a flat cross-piece 14, extending from one end piece to the other and having therein a series of openings 15. These openings are arranged in two rows longitudinally of the cross-piece 14, near the edges of the cross-piece, and they incline downwardly and inwardly. Some distance

beneath the cross-piece 14 is another cross-piece 16, its top being concave. Beneath the cross-piece 16 is a vertical partition 17 to fill the space between the cross-piece 16 and the base and between the end pieces. At the 30 sides of the device are the uprights 18, to extend from one end piece to the other and to project straight upwardly a short distance from the base, and a series of straight rods 19 extend transversely of the device from one 35 of the parts 18 to the other through the partition 17. These straight rods are placed at points equidistant throughout the entire length of the device. They are arranged in the same horizontal plane at some distance 40 above the bottom 10.

Having thus described my invention, what I claim as new, and desire to secure by Letters Patent of the United States, therefore, is—

The design for a case for writing utensils, 45 substantially as shown and described.

HENRY B. BELDEN.
